FUEL FEED MEANS FOR HINGED LIQUID
FUEL BURNERSJames L. Breese, Santa Fe, N. Mex., assignor to
Oil Devices, Santa Fe, N. Mex., a limited part-
nership of Illinois

Application February 14, 1940, Serial No. 318,869

6 Claims. (Cl. 158—2)

My invention relates to an improvement in fuel oil burners, and has for one purpose the provision of improved means for delivering a liquid fuel to a burner.

Another purpose is the provision of such means which may cooperate with or form part of the hinging or supporting means for a furnace or burner door.

Another purpose is the provision of an improved fuel supply means for supplying liquid fuel to a burner which is hinged for removal outwardly from a furnace.

Another purpose is the provision of improved means for preventing air locks in liquid fuel supply lines used in connection with burner doors, hinge burners or the like.

Other purposes will appear from time to time in the course of the specification and claims.

I illustrate my invention more or less diagrammatically in the accompanying drawing wherein:

Fig. 1 is a horizontal section;

Fig. 2 is a partial front elevation; and

Fig. 3 is a section on an enlarged scale on the line 3—3 of Fig. 2.

Like parts are indicated by like symbols throughout the specification and drawing.

Referring to the drawing, 1 generally indicates any suitable furnace member, which may be mounted, for example, on any suitable supporting members, legs, or the like, indicated at 2. 3 is a burner door, which may have hinge lugs 4 aligned with fixed lugs 5 on the furnace structure. 6 is an air passage member extending inwardly of the door and in communication with an outer and perfectly closed burner housing 7, within which is an inner burner housing or pot 8, which may have a perforated wall. I illustrate, for example, a plurality of air inlets 8a, which communicate with the space between the sleeves 7 and 8. The sole air inlet for such space is the passage 6 on the door 3, which admits air to support combustion within the pot or inner sleeve 8. The air is admitted through the apertures 8a, and the heat of combustion in or above the pot vaporizes the fuel which is delivered along the below described liquid fuel passage 22. 9 indicates any suitable top baffle structure for the pot, with a central opening 10. It will be understood that the details of the burner itself do not of themselves form part of the present invention. For example, the top baffle 9 may under some circumstances be omitted. What is essential is that the air passage 6 may serve as means for supplying air to the space between the outer burner housing 7 and the pot 8. It will be un-

derstood that any suitable means, such as the top wall 11, and a bottom wall 12, may be employed for insuring that the air supplied to the space between the members 7 and 8 passes through any suitable apertures in the pot 8, in order to mix with the vaporized hydrocarbons within the pot 8.

I may employ any suitable means for mounting the above described burner structure on the door 3, but the passage member 6 may itself be employed as such a supporting means, and is so shown in Figs. 1 and 2.

15 indicates any suitable hollow hinge pin which may have a top washer 16, and is herein shown as having an open upper end as at 17. Mounted upon the lower end of the hinge pin 15, and preferably secured against relative movement in relation thereto, is a washer or body 18, into one side of which may be screw-threaded a fuel passage member 19. To it may be secured any suitable fuel pipe 20, herein shown as held by a tapered locking sleeve 21, the details of which do not of themselves form part of the present invention.

25 22 is a fuel line extending to a lower portion of the pot 8 and shown as extending inwardly through the air inlet passage 6. It is also provided with an outer end fitting 23, to which may be secured an end of the tube 20. A tapered locking sleeve 24 may be employed. It will thus be understood that any liquid fuel which is delivered to the interior of the hinge pin 15 will pass inwardly through the pipe 20 and the fuel passage 22 to the pot.

35 25 indicates any suitable float chamber, the details of which do not form part of the present invention. The float chamber may be in communication with a source of liquid fuel, as by a supply pipe 26. 27 indicates any suitable exterior lever or control member for controlling the rate of flow or the level of fuel within the float chamber 25. The fuel line 28 extends from the float chamber 25 to the fitting 18. It may be locked in position in any suitable manner, as by the compressible gland 29, located within a screw-threaded downward extension 30 of the fitting 18. 31 is any suitable locking cap screw-threaded upon the exterior of the member 30 and containing the housing and locking member 32 upwardly thrust against the gland 29. Thereby a fluid fuel flow connection is provided for delivering a liquid fuel to the interior of the hollow pin 15 and, specifically, to the interior of the fitting 18, from which it flows along the members 19, 20 and 22 to the burner pot 8. It will be understood that

this flow is not interrupted by a movement of the closure or door 3, with the burner, about the axis defined by the hollow hinge pin 15.

It will be realized that whereas I have described and illustrated a practical and operative device, nevertheless many changes may be made in the size, shape, number and disposition of parts without departing from the spirit of my invention. I therefore wish my description and drawing to be taken as in a broad sense illustrative or diagrammatic, rather than as limiting me to my precise showing.

The use and operation of my invention are as follows:

Broadly stated, I have combined air venting means for the fuel line with the hollow hinge pin 15. There is relatively little pressure involved, as the highest level of fuel in the float chamber 25 may, for example, be an inch above the level of delivery of the fuel to the burner. In practice air bubbles tend to affect the flow of the fuel, especially where a right angle or sharp angle bend is employed in a fuel pipe. I, therefore, run the fuel from the float chamber 25 directly to the hollow hinge pin or to the fitting 18. The hinge pin thereby performs the triple function of serving as a hinge or pivot for the door 3, of delivering fuel from the float chamber to the burner, and of providing a vent to the atmosphere to prevent air locking, or the like.

Whereas fuel may not actually flow through the hinge 15 proper, the hinge pin 15 and the fitting 18 may together be considered as forming a hinge structure which is vented to the atmosphere, as at 17, and which serves as means for delivering fuel to the burner, independent of the position of the door or closure 3 on its hinge.

Whereas I have shown fuel as flowing rather through the fitting 18 than through the hinge pin proper, it will be understood that under some circumstances it may be advantageous to have the fuel actually flow upwardly through the hinge pin, to have it taken off for the burner at a higher level.

I claim:

1. In combination with an outer heater housing, a door, a burner mounted on said door, a hollow hinge pin structure for said door, means for delivering a liquid fuel to said hinge pin structure, and means for delivering said liquid fuel from said hinge pin structure to said burner, the interior of the hinge pin structure being vented to the atmosphere.

2. In combination with an outer heater housing, a door hinged to said housing, a burner within said housing, a hollow hinge pin structure for said door, means for delivering a liquid fuel to said hinge pin structure, and means for delivering said liquid fuel from said hinge pin structure to said burner, the interior of the hinge pin structure being vented to the atmosphere.

3. In combination in a liquid fuel burning heater, a heater housing having a door aperture, a door for said aperture, a pot type burner including an outer closed burner housing and an apertured burner pot therewithin, means for supplying air to the space within said housing and for at the same time supporting the burner in spaced relation to the inner side of said door, including an air conduit member extending in-

wardly from the door to the burner housing, the interior of said member being open to the atmosphere, and means for supporting the door and for conveying fuel to the burner, including a hollow hinge pin for said door, said hinge pin being vented to the atmosphere at an upper portion thereof, a liquid fuel supply means including a liquid fuel conduit in communication with the interior of said hinge pin, and a fuel conduit extending from said hinge pin to said burner and including a portion extending inwardly through the burner supporting air conduit member.

4. A fuel feeding device for pot type liquid fuel burners including a hollow hinge pin, means for mounting it on a heater, an upper portion of said hinge pin being vented to the atmosphere, means for supplying liquid fuel to a lower portion of said hinge pin, a door mounted for movement about an axis defined by said hinge pin, and a liquid fuel passage extending from said hinge pin and movable with said door about the axis of rotation of said door.

5. In combination with an outer heater housing having an inlet aperture, a door adapted to close said aperture, a pot type burner mounted on said door, said burner including an outer shell and an inner shell, and means for connecting them in air tight relationship, a combined air inlet passage and burner support extending inwardly from said door to said outer shell and in communication both with the exterior of said outer housing and with the space between inner and outer shells, said inner shell having a plurality of air inlet apertures, which constitute the sole air escape means from the space between inner and outer shells to the interior of the outer housing, said burner being movable unitarily with said door into and out of the aperture closed by said door, a source of liquid fuel supply, a liquid fuel delivery duct in communication with said inner shell and adapted to deliver a liquid fuel to the bottom thereof, and fuel passage means extending between said duct and said source of liquid fuel supply and effective at all positions of the door.

6. In combination with an outer heater housing having an inlet aperture, a door adapted to close said aperture, a pot type burner mounted on said door, said burner including an outer shell and an inner shell, and means for connecting them in air tight relationship, a combined air inlet passage and burner support extending inwardly from said door to said outer shell and in communication both with the exterior of said outer housing and with the space between inner and outer shells, said inner shell having a plurality of air inlet apertures, which constitute the sole air escape means from the space between inner and outer shells to the interior of the outer housing, said burner being movable unitarily with said door into and out of the aperture closed by said door, a hollow hinge pin structure for said door, a source of liquid fuel supply means for supplying liquid fuel therefrom to a lower portion of said hinge pin structure, and a liquid fuel passage extending from said hinge pin structure and movable with the door and in communication with said inner shell and adapted to deliver a liquid fuel to the bottom thereof.

JAMES L. BREESE.
